STENCILING ATTACHMENT FOR PLATEN PRESSES

Howard W. Parmelee, Chicago, Ill., assignor to
Naz-Dar Company, Chicago, Ill., a corporation
of Illinois

Application May 31, 1932, Serial No. 614,487

11 Claims. (Cl. 101—114)

This invention relates to the art of stenciling designs in one or more colors on sheet material, such as cardboard, or the like, and the object is to provide mechanism which may be readily applied to the ordinary platen press to render the latter adaptable for paint process work.

In stenciling designs on sheet material it is the usual practice to wipe a batch of paint over a stencil or screen, portions of which have been 10 preliminarily treated to render them penetrable. The paint is moved over the stencil by means of a squeegee which is held in pressure-contact with the stencil during the wiping stroke. Until comparatively recently work of this class was done 15 by machines which depended largely upon hand operation. Recently there have been developed machines which do the work, for the most part, automatically. However, the automatic machines are necessarily of costly construction, because of 20 the large amount of mechanism required for effecting automatic operation of the printing frame, the squeegee, and the sheet feed mechanism.

I have found that the ordinary platen press, 25 which is in common use in practically all job-printing establishments, may be readily adapted for use in paint process work. In the regular operation of a platen press, such as the Gordon press, the printing is what may be termed a contact printing, that is, the press remains in closed 30 position only for an instant, since all portions of the bed of type strike the sheet simultaneously. In order to adapt such a press to the stenciling of designs by the use of a squeegee and a stencil 35 screen it is necessary to provide means whereby the press may be maintained in closed position a sufficient length of time to allow the squeegee to be moved over the stencil. Also it is necessary to change somewhat the motion of the inking 40 roller frame of the press in order to make it adaptable for operation of the squeegee.

The means provided in accordance with my invention for modifying the standard form of platen press in the aforementioned manner will be fully 45 understood from the following detailed description, which, taken in connection with the accompanying drawings, discloses a preferred embodiment thereof.

Referring to the drawings:

Fig. 1 is a side elevational view of a platen press 50 of the Gordon type, to which the novel stenciling attachment has been applied;

Fig. 2 is a front elevational view of the stencil-supporting frame and paint feed mechanism, the view being taken on line 2—2 of Fig. 1;

Fig. 3 is a transverse vertical section through the bed of the press taken on line 3—3 of Fig. 2, the view also showing the position assumed by the platen when the press is in open position;

Fig. 4 is a view similar to Fig. 3, showing the position of the parts in the closed position of the press; and

Fig. 5 is a section through the bed taken on line 5—5 of Fig. 2.

The general construction of a platen press of the Gordon type is well understood in the art, and therefore the press proper will only be described in sufficient detail to enable an understanding of the manner in which the novel stenciling attachment is applied thereto.

Referring to Fig. 1, the press frame is indicated generally by the numeral 8 and the platen, which is pivotally supported on the upper front portion of the frame 8, is indicated at 9. A feed table 10 is supported on the frame 8 immediately in front of the platen 9. The bed, which is indicated generally by the numeral 11, is pivotally connected at 12 to the base portion of the frame about which it swings to and from closed position against the platen. An inking roller frame 13 is pivotally supported on the bed 11 by a shaft 14, said frame being provided in accordance with the usual construction with roller-supporting arms 15 which, in the regular operation of the press, carry the inking rollers upwardly over the bed of type and onto an inking table 16. The bed 11 is swung to and from closed position by connecting rods 17, which are disposed on the opposite sides of the press. Rods 17 are eccentrically connected at one end with shaft 14

through stub shafts 18, which project from the opposite ends of said shaft 14, the other ends of said connecting rods 17 being connected to crank discs 19 by means of pins 21, which are eccentrically mounted on discs 19. Pins 21 have yielding connection with rods 17, the ends of said rods being provided with rectangular openings 22 in which are slidably mounted bearing blocks 23, the latter being journaled on pins 21 and being engaged at their opposite ends by coil springs 24 and 25, which are housed in cavities formed in rods 17, said springs being arranged to bear at their free ends against the ends of blocks 23.

The reason for providing a yielding connection between rods 17 and crank discs 19 will be hereinafter explained. Crank discs 19 are mounted on a shaft 26, the latter being driven in the usual manner from a main drive shaft 27 which is provided with a spur gear 28, having driving engagement with a spur wheel 29 carried on shaft 26.

85

90

95

100

105

110

A fly-wheel 31 is mounted on one end of the main drive shaft 27 to provide for smooth and uniform movement of the bed and platen.

The platen 9 is rocked about its supporting shaft 32 (Fig. 3) in timed relation with the movements of bed 11. However, the mechanism for rocking the platen is not shown, since it is well known in the art. The usual frisket frame 33 is pivotally connected at 34 to the platen. This frame is provided with a pair of gripper arms 35 for engaging the opposite edges of the sheet, and is also provided at its lower edge with a cam roller 37 which is journaled on a pin 36 carried by said frame 33. A cam piece 38, rigidly supported on the main press frame 8, engages roller 37 to control the movement of the frisket frame to and from closed position against the platen in timed relation with the opening and closing movements of the press.

20 The usual emergency adjustment is provided for preventing contact of the bed with the platen. This mechanism, which is shown in Figs. 1 and 2, comprises: a link 39 which is pivotally connected at 41 to an arm 42, the latter being rigid on stub shaft 18; a hand operated lever 43 fulcrumed at 44 to the frame; and a series of intermediate connecting links 45, 46, 47, 48 and 49 interposed between lever 43 and the lower end of link 39. It will be apparent from Fig. 1 that when lever 43 is moved to the right, link 39 will be raised, thereby turning shaft 14, together with the stub shaft 18, which is mounted eccentrically thereon, in a counterclockwise direction. The effect of this adjustment is to increase the effective length of connecting rods 17, thereby preventing complete closing of the press. By moving lever 43 back to the position shown in Fig. 1, the parts are returned to their normal position for allowing contact of the bed with the platen.

40 In order to adapt a platen press of the type which has just been described to the stenciling of designs, it is necessary to substitute a stencil, or screen, for the customary bed of type. This change is accomplished in accordance with my invention, by substituting for the usual form of chase, which is used in platen processes, a special chase which is designed to serve as a support for a stencil-supporting frame. The construction of this special form of chase, and the associated stencil-supporting frame, is shown in Figs. 3 and 5. In these figures the chase is indicated generally by the numeral 51 and consists of a box shaped frame, the bed of which is indicated at 52, the sides of said frame being indicated at 53. The chase is adapted to be demountably secured to bed 11 in the usual manner by means of chase hooks 54 and 55.

60 A screen or stencil 56 is supported on chase 51 in a rectangular frame 57, the latter consisting of metal strips 58, which are suitably connected together to form a rigid frame unit. The edges of the stencil 56 are secured to strips of wood 59, the latter being in turn secured to the metal frame pieces 58. The complete stencil frame unit, consisting of the metal rim pieces 58, the wooden rim portion 59, and the stencil 56, is hingedly secured to the chase frame by a pair of hinges 61, which interconnect the lower edge of the stencil frame to the adjacent rim portion 53 of the chase. The stencil frame is normally held in the position shown in Fig. 3, in which position the upper edge of the frame rests against a pair of stop bars 62, which are carried on the sides 53 of the chase. A pair of leaf springs 63, interposed between the chase and the upper edge of

stencil frame 57, urges the latter outwardly against stop bars 62. When pressure is applied to frame 57 upon closing of the press, springs 63 yield sufficiently to allow stencil frame 57 to pivot inwardly on the chase from the position shown in Fig. 3 to the position shown in Fig. 4.

Continuing the reference to Figs. 3 and 5, a wiping element, or squeegee, is mounted in chase 51 for reciprocation over stencil 56. In the embodiment shown, the squeegee consists of a rubber wiping element 64 which is movably secured by means of a clamp bar 65 to a cross bar or carriage 66, the latter being provided at its opposite ends with vertically disposed arms 67, having rollers 68 mounted thereon for engaging in guide channels or grooves 69, which are formed in the rim portions 53 of the chase frame. The squeegee carriage 66 is arranged to be reciprocated in the chase by the inking roller frame 13, which in the ordinary operation of the press is used to operate the inking rollers in well known manner. To this end, the arms 67 of the carriage 66 are provided with latterly projecting rods 71, which extend through slots 72 formed in the sides of the chase 51, the free ends of said rods 71 being arranged to connect with hooks 73 which are carried by the ends of inking roller supporting arms 15. The upper pair of roller supporting arms 15 which are used in the operation of the press when working with type, are not needed in the operation of the press for paint process work, and therefore simply may be left detached or if desired may be entirely removed from the inking roller frame.

In Fig. 3, the squeegee is shown positioned at the lower edge of the stencil, which is the position it occupies when the press is open. In Fig. 4, the parts are shown in the position occupied when the press is closed, and after the squeegee has traversed the stencil, it being noted that in this position the platen 9 has been moved against 110 stencil frame 57 to force the latter inwardly to bring the stencil 56 into pressure contact with wiping element 64, this inward movement of the stencil frame being permitted by the yielding of springs 63. In the closed position of the press, a 120 card or sheet 74, supported on platen 9, is held in contact with the outer face of stencil 56.

It will be apparent that some interval of time will be required for the squeegee to traverse or advance over the stencil 56, and it is therefore necessary to arrange the press so that it will remain in closed position, with the stencil 56 in contact with the sheet 74, for a length of time sufficient to permit movement of the squeegee over the stencil. As previously pointed out, the ordinary platen press remains closed only for an instant, since the bed of type contacts with all parts of the sheet simultaneously. To momentarily arrest the movement of bed 11 away from the platen, I substitute for the usual fixed connection between rods 17 and crank disks 19, the yielding connection between these parts hereinbefore described and shown in Fig. 1. Assuming the bed 11 to be in the open position shown in Fig. 1, it will be apparent that when crank disks 140 are turned from the position shown, through an arc of 180 degrees, bed 11 will be moved to the closed position shown in Fig. 4. However, as crank disks 19 continue to rotate from this intermediate closed position, they will not immediately cause movement of bed 11 away from the platen due to the fact that springs 25 will yield under the pressure from blocks 23 upon reversal in the direction of the latter. Therefore, the rods 17 will not be moved in direction to effect opening of 150

the press until blocks 23 have moved against the ends of the openings 22. This yielding or lost motion connection between rods 17 and the crank disks 19 thus serves to maintain the press in closed position for an interval of time sufficient to permit the squeegee to advance over the stencil.

In order to operate the squeegee from the customary form of inking roller frame provided for platen presses, it is necessary to slightly modify the connection between said frame and the press frame. In the usual form of platen press, the connection between these parts consists of a rigid bar which extends between a bracket 75 on frame 13 and a second bracket 76 on the press frame (Fig. 1). This rigid connecting bar serves to rock the inking roller frame about shaft 14 to carrying the inking rollers up onto table 16, while the bed is moving to closed position, and to move said rollers downwardly over the chase while the bed is moving to open position. This form of motion of the frame 13 must be modified somewhat when using the press for stenciling work inasmuch as it is necessary to hold the squeegee at the lower edge of the stencil until the bed is moved to closed position, and thereafter to quickly advance it over the stencil during the brief interval during which the press remains closed. To this end, I substitute for the usual rigid bar connection between brackets 75 and 76, a hinged bar connection consisting of an arm 77, connected at one end to bracket 75, and a second arm 78, connected at one end to bracket 76, said arms 77 and 78 being pivotally interconnected with one another at 79. Arm 78 is provided at its free end with a lateral projection 81, which carries an adjusting bolt 82 the lower end of which bears against arm 77. A stop or limiting connection is thus provided between arms 77 and 78. The squeegee carriage 66 is held at the lower edge of the stencil, as shown in Fig. 3, by a pair of latch arms 83, which are pivoted at 84 to the side members 53 of the chase frame, the lower ends of said latch arms engaging over arms 67 to obstruct upward movement of carriage 66. Arms 83 are normally held in this latching position by springs 85, which are positioned in wells formed in side portions 53 of the chase frame, said springs being arranged to bear against the lower portions of said arms to urge the latter in a clockwise direction, view in Fig. 3.

When the press is in the open position shown in Fig. 1, the squeegee carriage 66 is in the lowered position. As the press closes, arms 77 and 78 collapse or fold together due to the fact that the squeegee carriage is held against upward movement by arms 83. By the time the bed 11 has moved to closed position against the platen, arms 77 and 78 are in their extreme folded position with inking roller frame 13 still occupying the same position relative to the bed as that shown in Fig. 1. However, as soon as the bed 11 arrives at the completely closed position, latch arms 83 are released from arms 67, this being effected by engagement of gripper bars 35 with lateral projections 86 formed on the upper ends of arms 83. Said projections 86 are so designed that when engaged by bars 35 they will release arms 83 at the exact instant that the sheet 74 on the platen comes fully into contact with stencil 56. The squeegee carriage 66 being thus released, is very quickly moved upwardly across the stencil by the turning of inking roller frame 13 about shaft 14. This upward movement of the squeegee is a comparatively high speed motion due to the fact that inking roller frame 13 is considerably overbalanced on shaft 14 and, when released, will pivot

under its own weight in a counterclockwise direction, view in Fig. 1. If in a particular machine, the frame 13 is not sufficiently overbalanced, a spring or weights may be attached to the free end thereof to give the necessary quick upward movement of the squeegee. The squeegee is thus moved across stencil 56 while the latter is in contact with sheet 74 and forces paint through the penetrable areas of the stencil onto the sheet. During this upward stroke of the squeegee the stencil frame 57 is held in the position shown in Fig. 4 by reason of the pressure applied thereto by the platen 9 which collapses spring 63. The upward movement of the squeegee is arrested as the end of the active stroke is approached by the pair of leaf springs 88 (Fig. 3) which are positioned in the sides 53 of the chase frame, and which engage against rollers 68 to check the upward movement of the latter.

The squeegee is moved from the upper edge of the stencil downwardly to the lower edge thereof during the interval of opening of the press, this being accomplished by movement of inking roller frame 13 from raised to lowered position, which movement carries the squeegee carriage 66 downwardly to the lower edge of the chase frame. In this position latch arms 83 engage over arms 67 to hold the squeegee in the lowered position shown in Fig. 3. The lower limiting position to which the squeegee carriage 66 is thus moved 105 may be regulated by adjusting screw 82 which interconnects arms 77 and 78. As soon as the bed 11 moves away from the platen 9, the stencil-supporting frame 57 is pushed outwardly on the chase by springs 63 thereby avoiding contact of 113 wiping element 64 with the stencil while the squeegee is being returned to the lower edge of the stencil. By hingedly mounting the stencil frame in this manner, so as to always make the squeegee active upon the upstroke and inactive upon 115 the downstroke I am able to prevent troublesome accumulations of paint in the stencil frame.

I have found that paint can be continuously supplied in drops or in a thin stream, from a container 89 which is supported on chase 51 by a 120 bracket 91. An outlet opening in the lower edge of container 89 is positioned so that paint will drop therefrom directly onto wiping element 64, from which point it flows against stencil 56. A manually controlled valve 92 is provided for regulating the rate at which paint flows from the container onto the wiping element 64. The printed sheet is pulled from the stencil by means of a rubber band 93 (Fig. 5), which is stretched between the upper ends of gripper bars 35. The paint has the consistency of a thick paste, and there is a considerable tendency for the sheet to stick to the stencil after it has been printed. It is, therefore, usually necessary to use the rubber band 93, or some equivalent means, to effect separation of the printed sheet from the stencil.

The equipment which is required for thus adapting the ordinary platen press to paint process work is relatively simple and inexpensive. The special form of stencil-supporting chase frame is so designed that it may be substituted for the ordinary chase frame without difficulty. Furthermore the provision of a yielding connection between rods 17 and crank disks 19, and the use of a hinged connection between brackets 75 and 76 in lieu of the ordinary connection, are changes which may be easily made. The entire equipment which is required to adapt the press to paint process work may be supplied to the trade in the form of an attachment which may 150

be readily applied to and removed from the press as desired. The invention thus in effect makes a single machine adaptable for ordinary printing work as well as for stenciling operations. I have 5 found that the quality of designs obtainable with a press of this type is vastly superior to the results obtainable by the older hand methods of operation. Also there is a substantial saving in cost, inasmuch as a single operator may turn out 10 a much larger volume of work than could be produced by several operators using a hand operated machine.

The foregoing detailed description has been given for clearness of understanding only, and no 15 unnecessary limitations should be understood therefrom, but the appended claims should be construed as broadly as permissible in view of the prior art.

What I regard as new and desire to secure 20 by Letters Patent is:

1. In a press for printing sheet stock and the like, the combination with a frame, a platen pivotally supported thereon, a bed, an inking frame supported for turning movement on the bed, 25 means providing pivotal support for said bed on the frame, and means for periodically moving said platen and the bed about their points of pivotal support to and from printing position relative to one another, of a stencil, a stencil-supporting frame adapted to be mounted on the bed in position to register with the platen in the closed position of the press, a squeegee mounted in said frame for reciprocation over the stencil, means operatively connecting said inking frame 30 with the squeegee, means for supplying paint to the stencil, means for periodically arresting movement of the bed away from the platen, whereby to momentarily maintain the press in closed position, and means for turning said inking frame to advance the squeegee over the face of 35 the stencil while the latter remains in contact with the sheet to be printed.

2. In a press for printing sheet stock and the like, the combination with a frame, a platen pivotally supported thereon, a bed, an inking frame supported for turning movement on the bed, 45 means providing pivotal support for said bed on the frame, and means for periodically moving said platen and the bed about their points of pivotal support to and from printing position relative to one another, of a stencil, a stencil-supporting frame adapted to be mounted on the bed in position to register with the platen in the closed position of the press, a squeegee mounted in said frame for reciprocation over the stencil, means operatively connecting said inking frame 50 with the squeegee, means for supplying paint to the stencil, means for periodically arresting movement of the bed away from the platen, whereby to momentarily maintain the press in closed position, and means for turning said inking frame to advance the squeegee over the face of the stencil while the latter remains in contact with the sheet to be printed, said last mentioned means being operative to return the squeegee to the rear edge of the stencil after the latter has been removed from the printed sheet and before it is returned to printing position relative to the platen. 60

3. In a press for printing sheet stock and the like, the combination with a frame, a platen pivotally supported thereon, a bed, an inking frame supported for turning movement on the bed, 65 means providing pivotal support for said bed on the frame, and means for periodically moving

said platen and the bed about their points of pivotal support to and from printing position relative to one another, of a stencil, a stencil-supporting frame adapted to be mounted on the bed in position to register with the platen in the closed position of the press, a squeegee mounted in said frame for reciprocation over the stencil, means operatively connecting said inking frame with the squeegee, means of supplying paint to the stencil, means for periodically arresting movement of the bed away from the platen, whereby to momentarily maintain the press in closed position, means for turning said inking frame to advance the squeegee over the face of the stencil while the latter remains in contact with the sheet to be printed, said last mentioned means being operative to return the squeegee to the rear edge of the stencil after the latter has been removed from the printed sheet and before it is returned to printing position relative to the platen, and means preventing contact of the stencil with the squeegee during return movement of the latter to the rear edge of the stencil. 95

4. In a press for printing sheet stock and the like, the combination with a platen, a bed, and means for periodically moving the latter to and from printing position relative to the platen, of a chase supported on the bed, a stencil, a stencil-supporting frame movably supported on the chase in position to register with the platen in the closed position of the press, a squeegee mounted in the chase for reciprocation over the stencil, means for supplying paint to the stencil, means for periodically arresting movement of the bed away from the platen whereby to momentarily maintain the press in closed position, means for advancing the squeegee over the face of the stencil while the latter remains in contact with the sheet being printed, said last-mentioned means being operative to return the squeegee to the rear edge of the stencil after the latter has been removed from the printed sheet and before it is returned to printing position relative to the platen, and means operative upon movement of the bed away from the platen to move the stencil-supporting frame to position preventing contact of the stencil with the squeegee during movement of the latter through the return stroke. 115

5. In a press for printing sheet stock and the like, the combination with a platen, a bed, and means for periodically moving the latter to and from printing position relative to the platen, of a stencil, a stencil-supporting frame adapted to be mounted on the bed in position to register with the platen in the closed position of the press, a squeegee mounted in said frame for reciprocation over the stencil, means for supplying paint to the stencil, means for periodically arresting movement of the bed away from the platen, whereby to momentarily maintain the press in closed position, means for advancing the squeegee over the face of the stencil while the latter remains in contact with the sheet to be printed, said last mentioned means being operative to return the squeegee to the rear edge of the stencil after the latter has been removed from the printed sheet and before it is returned to printing position relative to the platen, and means for engaging and holding the squeegee at the rear edge of the stencil upon completion of the return stroke, said last-mentioned means being operative to release the squeegee upon movement of the bed to printing position. 145

- like, the combination with a platen, a bed, and means for periodically moving the latter to and from printing position relative to the platen, of a stencil, a stencil-supporting frame adapted to be mounted on the bed in position to register with the platen in the closed position of the press, a squeegee mounted in said frame for reciprocation over the stencil, means for supplying paint to the stencil, means for periodically arresting movement of the bed away from the platen, whereby to momentarily maintain the press in closed position, means for advancing the squeegee over the face of the stencil while the latter remains in contact with the sheet to be printed, said last-mentioned means being operative to return the squeegee to the rear edge of the stencil after the latter has been removed from the printed sheet and before it is returned to printing position relative to the platen, means for engaging and holding the squeegee at the rear edge of the stencil upon completion of the return stroke, said last-mentioned means being operative to release the squeegee upon movement of the bed to printing position, and means operative upon movement of the bed away from the platen to move the stencil and its supporting frame to a position preventing contact of the stencil with the squeegee during movement of the latter through the return stroke.

7. In a press for printing sheet stock and the like, the combination with a bed, a platen, including a frisket frame pivotally supported thereon, and means for periodically moving the bed and platen to and from printing position relative to one another, of a stencil, a stencil-supporting frame adapted to be mounted on the bed in position to register with the platen in the closed position of the press, a squeegee mounted in said frame for reciprocation over the stencil, means for supplying paint to the stencil, means for periodically arresting movement of the bed away from the platen, whereby to momentarily maintain the press in closed position, means for advancing the squeegee over the face of the stencil while the latter remains in contact with the sheet to be printed, and means extending between the arms of the frisket frame for engaging the sheet to effect separation thereof from the stencil upon movement of the bed and platen to open position.

8. In a press for printing sheet stock and the like, the combination with a bed, a platen, including a frisket frame, and means for periodically moving the bed and platen to and from printing position relative to one another, of a stencil, a stencil-supporting frame adapted to be mounted on the bed in position to register with the platen in the closed position of the press, a squeegee mounted in said frame for reciprocation over the stencil, means for supplying paint to the stencil, means for periodically arresting movement of the bed away from the platen, whereby to momentarily maintain the press in closed position, means for advancing the squeegee over the face of the stencil while the latter remains in contact with the sheet to be printed, said last-mentioned means being operative to return the squeegee to the rear edge of the stencil after the latter has been removed from the printed sheet and before it is returned to printing position relative to the platen, and latch mechanism for engaging and holding the squeegee at the rear edge of the stencil upon completion of the return stroke, said mechanism being arranged to be engaged by the frisket frame to effect release of the squeegee upon movement of the bed to printing position against the platen.

9. In a platen press for printing sheet stock and the like, the combination of a frame, a bed pivotally supported on the frame, drive means including a crank disk supported on the frame and a crank arm interposed between said disk and the bed for periodically moving the latter to and from closed position against the platen, a stencil, a stencil-supporting frame mounted on the bed in position to register with the platen in the closed position of the press, a squeegee mounted in said frame for reciprocation over the stencil, means for supplying paint to the stencil, means comprising a yielding connection between said crank disk and arm for periodically arresting movement of the bed away from the platen whereby to momentarily maintain the press in closed position, and means for advancing the squeegee over the face of the stencil while the press remains in closed position.

10. In a platen press for printing sheet stock and the like, the combination of a frame, a bed pivotally supported on the frame, drive means including a crank disk supported on the frame and a crank arm interposed between said disk and the bed for periodically moving the latter to and from closed position against the platen, a stencil, a stencil-supporting frame mounted on the bed in position to register with the platen in the closed position of the press, a squeegee mounted in said frame for reciprocation over the stencil, means for supplying paint to the stencil, means comprising a yielding connection between said crank disk and arm for periodically arresting movement of the bed away from the platen whereby to momentarily maintain the press in closed position, and means for advancing the squeegee over the face of the stencil while the press remains in closed position.

11. In a press for printing sheet stock and the like, the combination with a platen, a bed, and means for periodically moving the latter to and from printing position relative to the platen, of a stencil, stencil-supporting frame adapted to be mounted on the bed in position to register with the platen in the closed position of the press, a squeegee mounted in said frame for reciprocation over the stencil, means for supplying paint to the stencil, means for periodically arresting movement of the bed away from the platen, whereby to momentarily maintain the press in closed position, an inking frame supported for turning movement on the bed, means operatively connecting said frame with the squeegee, a connecting member interposed between the press frame and said inking frame for turning the latter to move the squeegee from the upper to the lower edge of the stencil upon movement of the bed away from the platen, latch mechanism for engaging and holding the squeegee at the lower edge of the stencil pending movement of the bed to closed position, said latching mechanism being arranged to release the squeegee upon movement of the bed to closed position and said inking frame being over-balanced upon its point of support whereby to effect rapid upward movement of the squeegee over the face of the stencil while the latter remains in contact with the sheet to be printed.

HOWARD W. PARMELE.
